UNITED STATES PATENT OFFICE.

GUSTAV UNTERBERG, OF DURLACH, GERMANY.

APPARATUS FOR STARTING INTERNAL-COMBUSTION ENGINES.

1,089,294.

Specification of Letters Patent.

Patented Mar. 3, 1914.

Application filed March 26, 1912. Serial No. 686,273.

To all whom it may concern:

Be it known that I, GUSTAV UNTERBERG, engineer, a citizen of the German Empire, residing at Durlach, Baden, Germany, have 5 invented certain new and useful Improvements in Apparatus for Starting Internal-Combustion Engines, of which the following is a specification.

Apparatus for starting internal combustion engines from the driver's seat are in themselves known. These are arranged so that the armature of the dynamo electric generator for the ignition of the internal combustion engine is driven, by a device for 10 accelerating the armature, set in operation or released from the driver's seat, in the magnetic field at a suitable speed in order to produce an igniting spark in the cylinder which in the position of rest of the engine is 15 on compression and contains some of the mixture of gas and air. In order to insure that these arrangements will work with certainty it is naturally necessary that some explosive mixture be present in the cylinder 20 and further that this mixture be under the highest possible pressure. However, experience shows that in very many cases, the fast moving piston as well as the valves, because of their incessant movements in the operation 25 of the engine, do not remain long in a condition for retaining the explosive mixture under pressure while the engine is at rest, if the valves and piston are very efficient in the normal operation of the engine. 30 Now in order to render this unavoidable leakage of the piston and valves harmless, according to this invention, reservoirs are joined to each explosion cylinder with intermediate back pressure valves which by 35 means of regulating members are actuated from outside so that the passages to the reservoirs are closed while the engine is working; the passages are open upon the stopping of the engine and upon the interruption 40 of the ignition by the release of the back pressure valve for the compressed mixture. Again upon the starting of the engine before or during the release of the ignition apparatus the passages are freely connected to the cylinder. As these closing 45 members and back pressure valves only come into operation upon the starting and stopping of the engine they can afford a reliable gas tight joint for a sufficient 50 length of time. By closing the passages between the reservoirs and the explosion cylinder-

ders by means of a cock or by fixing the back pressure valve, a disadvantageous compression space may be avoided. By connecting the controlling rod for the cock between the reservoir and the explosion cylinder to the controlling rods for the throttle and the ignition it is possible to operate the engine in a simple manner by a single handle at the driver's seat and at the same time to obtain the necessary energy for starting the engine and further to release this energy at the same time by a single movement of the ignition lever. The size of the reservoirs must entirely depend upon the volume of the cylinder. It need only be of a limited size for large cylinders. Also this arrangement can be carried out so that for all the cylinders only a single reservoir is necessary. Instead of a back pressure valve which is shut when the engine is working, is open when the engine and ignition is cut off, and is released when the engine is started up, any other equivalent device may be employed.

In the accompanying drawings, the back pressure valve is combined with a closing cock which locks the passages between the reservoirs and cylinders when the engine is working, opens the passages from the valves when the engine is switched off and releases the valves when the engine is started up.

Figure 1 is a broken side elevation of the controlling mechanism of a motor car with ignition apparatus and explosion cylinders with the reservoirs according to the invention. Figs. 2 and 3 are central vertical sectional views taken transversely and longitudinally, respectively, of the engine and showing the valves in the passage between the reservoir and cylinder.

a, b, c, d, are the cylinders with the sparking plugs *e, f, g* and *h*.

i is a magneto ignition apparatus provided with an auxiliary device which is arranged in a manner, in itself known, between the armature and the armature driving shaft and has an armature accelerating device which on switching in the ignition apparatus is wound up and released to drive the armature.

k, l, m, n are the bottle shaped reservoirs. In the passages *o* between these bottles and the cylinders *a, b, c, d*, as is shown in Figs. 2 and 3, the back pressure valves formed of ordinary balls *p* and a cock *q* are arranged. As is shown in Fig. 1, all the cocks *q* are ar-

ranged on a common spindle r which is operated through the driving rod s . This rod is fastened to the controlling rod t for the ignition apparatus.

5 The method of working of this mechanism is as follows:—As soon as the ignition apparatus for the running engine is switched off from the driver's seat through the control wheel u by means of the rods t by which 10 at the same time, as already described, the armature starting device in the ignition apparatus i is wound up, the passage o from the reservoirs k, l, m, n are opened by means of the cocks q so that the rotating masses 15 of the engine can compress in the reservoirs against the action of the back pressure valves p . When the engine is at rest the back pressure valve p separates the contents of the reservoirs k, l, m, n from the outside 20 so that the mixture can escape from the cylinders in case the valves and piston, as is often the case, do not make quite tight joints. On starting up the engine it is only necessary to operate the controlling member 25 u at the driver's seat. By this means the drive of the ignition apparatus i is released and at the same time the cocks q are operated through the rod s and the spindle r so that the upper edge of the plug in the cock 30 q pushes up the ball p as is seen in Figs. 2 and 3. This puts the spaces in the reservoirs k, l, m, n in communication with the cylinders a, b, c, d , for a moment and then the cock q shuts the passage o again, of course, 35 either at the seat of the back pressure valve p or at the opposite opening of the plug in the cock. Thus it is by this arrangement of passages that opening and closing is effected by two movements of the cock q and by the 40 movement from open position to closed position the back pressure valve is pushed up. The construction of this controlling mechanism may be varied for it is only necessary that the back pressure valve is closed during 45 the operation of the engine, is open during the stopping of the engine and is pushed open during the starting of the engine. In the present case the cock serves as a controlling member and during the running of 50 the engine it also acts to close the passage o .

It is obvious that the reservoirs for the cylinders are also to be employed in other arrangements for starting up internal combustion engines and, of course, especially for 55 those in which the ignition apparatus for the production of sparks is driven from a device at the driver's seat.

Claims.

1. Apparatus for starting internal combustion engines consisting of a reservoir 60 connected to each cylinder of the engine, back pressure valves arranged in the passages between said reservoirs and cylinders

and means for controlling said valves, whereby they are closed during the running 65 of the engine and opened during the starting and stopping thereof.

2. Apparatus for starting internal combustion engines consisting of a reservoir connected to each cylinder of the engine, 70 back pressure valves arranged in the passages between said reservoirs and cylinders and means for controlling said valves connected to the ignition controlling devices, whereby said valves are closed during the 75 running of the engine and opened during the starting and stopping thereof.

3. Apparatus for starting internal combustion engines consisting of a reservoir connected to each cylinder of the engine, 80 automatic valves interposed between said reservoirs and cylinders, and valves adapted to open communication between the cylinders and the reservoirs to allow the latter to be charged.

4. Apparatus for starting internal combustion engines consisting of a reservoir connected to each cylinder of the engine, automatic valves interposed between said reservoirs and said cylinders, valves adapted 90 to open communication between the cylinders and the reservoirs to allow the latter to be charged, and means for opening the automatic valves to allow the compressed gas to escape into the cylinders of the motors. 95

5. Apparatus for starting internal combustion engines consisting of a reservoir connected to each cylinder of the engine, automatic valves interposed between said cylinders and said reservoirs, valves adapted to open communication between the cylinders and the reservoirs to allow the latter to be charged, and means for controlling the last named valves whereby they are closed during the running of the engine and 105 opened during the starting and stopping thereof.

6. Apparatus for starting internal combustion engines consisting of a reservoir connected to each cylinder of the engine, 110 automatic valves interposed between said reservoirs and said cylinders, valves adapted to open communication between the cylinders and the reservoirs to allow the latter to be charged, and means for controlling the last named valves connected to the ignition controlling devices whereby said valves are closed during the running of the engine and opened during the starting and stopping thereof. 115

In testimony whereof I affix my signature, in presence of two witnesses.

GUSTAV UNTERBERG.
